By Henry Orth Atty.

UNITED STATES PATENT OFFICE.

JENS WILLIAM ÆGIDIUS ELLING, OF CHRISTIANIA, NORWAY, ASSIGNOR TO A/S
MYRENS VERKSTED, OF CHRISTIANIA, NORWAY.

ARRANGEMENT FOR DRYING SOLID LIQUID-CONTAINING BODIES.

1,347,501.

Specification of Letters Patent.

Patented July 27, 1920.

Application filed February 21, 1919. Serial No. 278,551.

To all whom it may concern:

Be it known that I, JENS WILLIAM ÆGIDIUS ELLING, a subject of the King of Norway, of Christiania, in the Kingdom of Norway, have invented certain new and useful Improvements in Arrangements for Drying Solid Liquid-Containing Bodies; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The present invention relates to an arrangement for drying solid liquid-containing bodies such as fish, fruits, vegetables, etc., and the object of the invention is to provide an arrangement for carrying out this kind of drying process without exposing the drying products to high temperatures or strong currents of drying air.

This is obtained according to the present invention by separating the heating medium from the drying goods by means of a thin flexible wall and keeping the heating medium at a higher pressure than the drying goods in such a manner that the said thin flexible wall is pressed against the drying goods.

According to a suitable form of the invention the medium is conducted into bags of flexible material, which communicate at one end with the heating chamber or channel, while with their two other ends they project into the drying chamber between the drying goods.

On the drawing:

40 Figure 1 is a vertical sectional view on the line A, B of Fig. 2 illustrating a practical embodiment of the invention.

Fig. 2 is a section on the line C, D of Fig. 1.

45 1 is the heating vessel which is supplied with steam through inlet tube 2 and is provided with an outlet 4 for condensed steam. This vessel 1 is covered with a hood 6 which is mounted gastight on the part 1, and the 50 interior of which communicates with an out-

let 3, which may be connected to a suction device or the like.

Bags 5 of flexible material are arranged in rows inside hood 6 with the bottom up and their openings secured between rods or ribs 9 covering the top opening of steam chamber 1. The bags 5 may be maintained in their upright position by means of wire frames 7, 8 or the like.

The material to be dried is indicated by 60 number 10 and is placed between the flexible bags 5. When steam pressure is put on chamber 1 the flexible bags extend and press against the material to be dried so that the heat is transmitted directly through the 65 flexible walls to the drying goods.

I claim:

1. In an apparatus for drying solid materials a chamber supplied with heating medium and a chamber containing the material to be dried, the pressure in said last chamber being lower than the pressure in the heating chamber and bags of flexible material extending into the drying chamber and communicating with the heating chamber said bags being spaced apart to give room for the goods to be placed between them.

2. In an apparatus for drying solid materials a chamber supplied with heating medium and a chamber containing the material to be dried, the pressure in said last chamber being lower than the pressure in the heating chamber a row of bags of flexible material extending with their bottom up 85 into the drying chamber and having their openings in communication with the heating chamber.

3. In apparatus for drying solid materials, a heating chamber supplied with a heating medium, and a drying chamber for containing the material to be dried, in which the pressure is lower than in the first chamber, flexible bags extending upward from the heating chamber into the drying 95 chamber, and distending and supporting elements for the bags.

4. In apparatus for drying solid materials, a heating chamber supplied with a heating medium, a drying chamber formed 100

by a removable hood on the heating chamber for containing the material to be dried, and flexible bags extending upward from the heating chamber into the drying chamber and between which the material to be dried is placed, said drying chamber adapted to be placed under suction.

In testimony that I claim the foregoing as my invention, I have signed my name in presence of two subscribing witnesses.

JENS WILLIAM AEGIDIUS ELLING.
